UNITED STATES PATENT OFFICE.

HARRISON W. ROGERS, OF NEW YORK, N. Y.

SOUND-RECORDING APPARATUS.

1,119,317.

Specification of Letters Patent.

Patented Dec. 1, 1914.

Application filed October 11, 1913. Serial No. 794,631.

To all whom it may concern:

Be it known that I, HARRISON W. ROGERS, a citizen of the United States, residing at New York, in the county of New York and 5 State of New York, have invented a new and useful Sound-Recording Apparatus, of which the following is a specification.

The present invention relates to improvements in sound recording apparatus, and 10 more particularly to that type of apparatus, in which the stylus for producing the sound indentations upon a record is operated electromagnetically, one object of the present invention being the provision of a simple 15 mechanism by means of which the throw of the stylus carrying member is regulated as is also the armature controlled by the electromagnet, which forms a part of a bi-polar structure, somewhat similar to the usual 20 form of telephone receiver.

With the foregoing and other objects in view which will appear as the description proceeds, the invention resides in the combination and arrangement of parts and in 25 the details of construction hereinafter described and claimed, it being noted that changes in the precise embodiment of the invention herein disclosed can be made within the scope of what is claimed without departing from the spirit of the invention.

In the drawings—Figure 1 is a view in elevation and in diagram of the present apparatus. Fig. 2 is an enlarged view of a portion of the stand, with the recording apparatus in longitudinal section. Fig. 3 is a top plan view upon a small scale of the complete cabinet, supporting arm and recording device. Fig. 4 is an end view of the recording device taken from the stylus carrying portion thereof. Fig. 5 is a section taken on line 5—5 of Fig. 2.

Referring to the drawings, the numeral 1 designates the cabinet or stand, of the recording machine, which has supported 45 at one side thereof, the upstanding post 2, which by means of the screw 3 forms a pivotal support for the arm 4. This arm has mounted upon the free end thereof, the adjustable counterbalancing weight 5, while 50 attached to the depending end thereof, is the electrically actuated recording device 6. This device, as clearly shown in detail, in Fig. 2, consists of an outer casing having the head 7, and carrying therewithin the bi-polar permanent magnet 8. Connected to

the poles of the magnet 8 is one or more electromagnets 9, the cores 10 of which are disposed to affect the pivoted armature 23, as will presently appear.

Detachably connected to the opposite end 60 of the casing from the head 7 is a disk cap 11, provided with the central aperture 12 and with the downwardly depending and outwardly curved arm 13 in whose apertured and bifurcated end 14 is mounted the removable pin 15 which is adapted to seat in one of the apertures 16 of the stylus carrying rod 17 and thus properly support the rod 17 so that the stylus or needle 18 will be disposed in recording relation to the wax 70 disk 19, which is disposed to be rotated by any mechanism (not shown) disposed within the cabinet or casing 1. A pin 20 is adapted to be inserted in any one of the apertures 21 at the upper end of the rod 17 75 to pivotally connect the rod or bar 22 to the upper end of said rod 17, such rod 22 being extended through the aperture 12 of the disk 11 and operably connected to the free end of the armature 23. This armature 23 is pivoted at 24 to the bracket 25 carried by the casing of the recording apparatus, the armature being disposed in attractive relation to the core 10 of the coil 9 so that the armature 23 is thus influenced by the fluctuations of 80 current so that the rod 17 is vibrated and consequently the stylus and needle 18 is vibrated to produce the desired or lateral sound producing indentations upon the disk 19. The disk 19 is a spiral groove disk, 90 the grooves being primarily formed therein so that the rotation of such disk during the producing of a record will cause the arm 4 and consequently the recording device 6 through the engagement of the stylus or 95 needle 18 with such groove to move from the outer periphery of the disk toward the center, or vice versa, as may be desired.

In order to provide a means for adjusting the armature 23 and consequently the 100 air gap between it and the pole or core 10, a rod 26 is connected to the rod or bar 22 and is operably connected to the lever 27, said lever 27 being mounted in the bracket 28 while the end of the lever opposite to the 105 rod 26 is operably connected to the threaded rod 29 which by means of the adjusting nut 30 is operated to tilt the lever and consequently move the armature 23 to and from the pole 10 of the magnet 9. By this means, 110

the armature 23 may be properly adjusted to regulate the air gap and thus secure the best possible results in making the record.

5 A diaphragm 31 may or may not be carried in the recording apparatus, the same being operably connected to the armature 23, so as to be vibrated thereby simultaneously with the vibration of the rod 22.

10 In connecting the present device in circuit for electrical actuation, the conductors 32 and 32' are led from the coil 9 to the respective binding posts 33 and 33' mounted in and insulated from the cap 7. As shown in Fig. 1, the batteries 34, which may be 15 taken indicative of any source of electrical energy, have the circuit conductor 35 led therefrom and disposed in the said conductor either in multiple or in series, are a plurality of microphone transmitters 36, which 20 are operably connected to the binding posts 33 and 33' to thus influence the electromagnet 9 and consequently its pole or core 10. A switch 37 is connected in the circuit so 25 that the circuit may be opened at any desired time.

What is claimed is:

1. A recording apparatus including a permanent magnet, a casing, coils, each having a pole piece under the influence of the permanent magnet, a pivoted armature mounted within the casing and disposed with its free end in attractive relation to the pole pieces, a stylus guiding member pivoted intermediate of its ends to the casing exteriorly thereof, means capable of being flexed connecting the free end of said member to the armature, and manually operable means for flexing said connection to regulate the air gap between the pole pieces and armature. 35

diate of its ends to the casing exteriorly thereof, means capable of being flexed connecting the free end of said member to the armature, and manually operable means for flexing said connection to regulate the air gap between the pole pieces and armature. 40

2. A recording apparatus including a permanent magnet, a casing, coils, each having a pole piece under the influence of the permanent magnet, a pivoted armature mounted in the casing and disposed with its free end in attractive relation to the pole pieces, a 45 stylus guiding member pivoted intermediate of its ends to the casing exteriorly thereof, means capable of being flexed connecting the free end of said member to the armature, a lever pivoted intermediate of its ends 50 within the casing, a rod connecting one free end of the lever to the connection, a threaded stem connected to the other end of the lever and extending exteriorly of the casing, and a manually operable nut upon the 55 threaded stem for actuating the lever to flex the connection to regulate the air gap between the armature and the pole pieces.

In testimony that I claim the foregoing as my own, I have hereto affixed my signature in the presence of two witnesses. 60

HARRISON W. ROGERS.
